CLAIM

The ornamental design for a teeth whitening mouthpiece, as shown and described.

DESCRIPTION

FIG. 1 is an upper right and rear perspective view of a teeth whitening mouthpiece showing my new design.

FIG. 2 is an upper left and front perspective view thereof.

FIG. 3 is a top plan view thereof.

FIG. 4 is a front elevational view thereof.

FIG. 5 is a right side elevational view thereof.

FIG. 6 is a top plan view of a second embodiment of a teeth whitening mouthpiece showing my new design;

FIG. 7 is a front elevational view thereof; and,

FIG. 8 is a right side elevational view thereof.
